UNITED STATES PATENT OFFICE.

JOHN DIERDORF, OF INDIANAPOLIS, INDIANA.

DESIGN FOR A PIANO-BACK.

SPECIFICATION forming part of Design No. 32,548, dated April 17, 1900.

Application filed March 7, 1900. Serial No. 7,737. Term of patent 7 years.

To all whom it may concern:

Be it known that I, JOHN DIERDORF, a citizen of the United States, residing at Indianapolis, in the county of Marion and State of Indiana, have invented a certain new and original Design for Piano-Backs, of which the following is a specification.

Figure 1 is a perspective view of my piano-back, showing my new design; and Fig. 2 is a central vertical section of the same as seen when looking in the direction indicated by the arrows on the line 2 2 in Fig. 1.

As shown in the drawings, the leading or material features of my new design are a rectangular metal back 1, having the integral projecting flange 2 around the outer edge thereof, a square sounding-opening centrally located within the plate 1 and having the pro-

jecting flange 3 around said opening, an arched flange 4 across the face of the plate 1, above the sounding-hole, and strengthening-brackets 5, placed at intervals, which connect the flanges 2 and 3.

Having thus fully described my said invention, what I desire to secure by Letters Patent is—

The design for a piano-back, as herein shown and described.

In witness whereof I have hereunto set my hand and seal, at Indianapolis, Indiana, this 10th day of January, A. D. 1900.

JOHN DIERDORF. [L. S.]
